United States Patent

Des. 236,357
Patented Aug. 19, 1975

236,357

CABINET FOR A DATA SYSTEM

Richard G. Clayton, Detroit, Mich., assignor to
Burroughs Corporation, Detroit, Mich.

Filed Sept. 20, 1973, Ser. No. 399,124

Term of patent 14 years

Int. Cl. D14—02

U.S. Cl. D26—5 C

The single figure is a front perspective view of a cabinet for a data system showing my new design.

The rear and the side of the article not shown are substantially planar and unornamented.

I claim:

The ornamental design for a cabinet for a data system, substantially as shown and described.
